UNITED STATES PATENT OFFICE.

WILLIAM H. FORD, OF LOWELL, MASSACHUSETTS.

MOLD-EXTRACTING APPARATUS.

1,118,194.

Specification of Letters Patent.

Patented Nov. 24, 1914.

Continuation of application filed March 19, 1910, Serial No. 550,424. This application filed April 15, 1912. Serial No. 690,766.

To all whom it may concern:

Be it known that I, WILLIAM H. FORD, a citizen of the United States, and resident of Lowell, county of Middlesex, State of Massachusetts, have invented an Improvement in Mold-Extracting Apparatus, of which the following description, in connection with the accompanying drawings, is a specification, like letters on the drawings 10 representing like parts.

My present invention relates to apparatus for preparing molds for casting operations and is herein, for convenience of explanation and illustration, shown applied to the 15 preparation of molds for small articles, such as rings, this typifying the more delicate classes of work, although it will be understood that it is not limited thereto. In my prior application, Ser. No. 550,424 filed 20 March 19, 1910, I have shown an apparatus of this kind provided with a lower shaping or forming receptacle mounted on a base, and adapted to receive thereover a molding frame, which frame, after the pattern or 25 patterns are properly placed in the sand and have given their shape to the latter, is removed, and the molds extracted therefrom by means of a mold extracting mechanism adapted for coöperation therewith. In said 30 prior application I have duly claimed the special improved construction of forming receptacle, with the molding frame and other parts coöoperative therewith for forming the molds, and in the present case, 35 which is a continuation thereof, I am claiming the improvements in the mold extracting mechanism and the combination therewith of the detachable frame portion of the mechanism.

40 The invention will be better understood from the following detailed description, taken in connection with the accompanying drawings, wherein a preferred embodiment is illustrated, and will be thereafter pointed 45 out in the appended claims.

Referring to the drawings, Figure 1 is an elevation, partly in section, of my improved mold extracting mechanism, showing the molding frame with molds therein fitted 50 in position for extraction of the molds; Fig. 2 is a central longitudinal vertical section through an illustrative form of mold forming apparatus, showing the manner of co-operation of the molding frame therewith;

and Fig. 3 is a vertical section on line 3—3 of Fig. 2.

The manner in which the molds are formed by the apparatus shown in Figs. 2 and 3 is explained in detail in my said prior application, and need be only briefly summarized herein to the extent necessary to show generally the requisites as to the construction of the molding frame, and the manner in which the molds are positioned and engaged therein.

A suitable foundation or support 10 has fixed thereon for convenient removal the bottom plate 11 of a receptacle or carrier 12 for the molding patterns and coöperative parts, the bottom plate 11 as shown extending out some little distance beyond the ends of this carrier or receptacle. The receptacle or carrier 12 has journaled in lugs at its upper portion oppositely threaded screw rods 13, 14 coöperative with slide blocks 15, 16, which are adapted to hold the patterns 17, 18 fixedly in place at the two sides of the receptacle. As shown, the patterns 17, 18 are the opposite complementary sides of a ring, the mold portions *a*, *b* in the two sides 80 being placed together to complete the ring mold. A casing to hold the mold portions *a*, *b* at the two sides for shaping them to proper dimensions is provided by a frame 19 which fits down over the receptacle or carrier 12, resting upon the bottom plate 11 thereof. This frame and the receptacle 12 are of oblong shape, and the frame 19 is divided centrally of its longer dimension by a partition 20 which is arranged midway 90 between the ends, so that the mold portions *a*, *b* are of exactly the same dimensions. The bottom of the casing spaces which form the mold portions *a*, *b* are constituted by the tops of the slide blocks 15, 16 with the pattern portions projecting upward therefrom, and the frame 19 is shown as provided with ledges 21 at either end for engaging the outer adjacent edges of such slide blocks. A filler 22 is formed to set on the top of the frame 19 to facilitate the filling of the mold spaces, this filler being removable from the top of the frame, as shown, by swinging about an axis 23 at one side of the frame and near its top, to permit shaving or cutting off 105 the mold material with a knife or other leveling tool, so that the top of the material is precisely level with the top edge of the

frame 19. The frame 19 is provided with suitable handles 24 extending from its opposite ends for lifting the frame, with the molds carried thereby, off of the patterns 5 and shaping receptacle. This is effected preferably after the molds have been cut down to exact size as stated, by a straight-up lifting movement, whereby the molds are disengaged and freed from the patterns 10 without any possibility of end or side shake or movement likely to break or disturb the delicate portions of the molded cavity, such as the tip portions of the ring clamps. This result is aided by the fact that the frame in 15 this lifting movement is guided over the receptacle 12 until the molds are well off of the patterns. The mold portions being thus removed and held in the frame 19, this frame is now set down on a mold extractor, shown 20 as comprising a plunger-like block 25 provided with a thumb screw or stud 26 for fitting into a slot 27 of a receiving pocket or strap 28, secured to the bench or other support 29, to immovably clamp said plunger block thereto. A rock-shaft 30 is journaled 25 in brackets or offsets 31 just below the strap 28, and is provided with forwardly projecting arms 32, through which extends in pivotal relation the central portion of a U-shaped rod or like member 33 whose ends 34 are provided with hooks 35 to engage the handles 24 of the frame, being normally held forward toward the bench, and hence 30 in position to engage said handles, by a coil spring 36 carried on the center portion 33, having a bearing against the arms 32 and acting on the end portions 34. Accordingly, when the operator has placed the frame 19 and its mold parts *a*, *b* on the top of the 35 plunger block 25, as shown in Fig. 1, he depresses the rock-shaft handle 37 which draws down powerfully on the rod or wire ends 34, and hence on the handles 24 of the frame, causing the mold parts *a*, *b* to be 40 accurately ejected or extracted by a true and straight-up movement, out of the frame as it is depressed. The lower cut-out portion of the frame 19 fits over the plunger block 25 and said block is preferably cut away to 45 provide ledges, as seen at 38, so as to limit the downward movement of the frame by the ledges 21 engaging therewith, thus also providing reduced top portions to follow behind the mold parts *a*, *b* and press them entirely out of the frame. The plunger top is 50 also provided with a central recess 39 to accommodate the central partition 20, this recess being of a size to be fitted by said partition. Preferably a metal band or plate 55 40 is set in the edge of the upper ends of the reduced parts of the plunger, so as to insure durability and maintain a level plane at the corners for lifting accurately the extreme corners or edges of the molds. Also, 60 preferably cavities 41 are provided in the 65

top of the plunger sufficient in area and located so as to extend over the width of the core and length of the pattern, so as to prevent any possibility of disturbing or interfering with the mold at these points.

70

When my invention is designed for the requirements of extremely fine work, such as jewelers' work, I preferably make the extractor of extremely hard material, such as indurated fiber that will not scratch the frame, which is made of metal. The complementary mold portions can thus be very readily and quickly removed from the frame 19, so that this frame is ready for further use, while the mold portions may be fitted 80 together and used for casting in the manner set forth in my said prior application. It is to be observed that the special construction of the extracting mechanism is arranged for coöperation with the special 85 form of the frame 19 as required by the mold forming parts, so that the construction of this frame enables it to be accurately held and guided for the ejection of the mold portions in a manner to best insure the removal 90 of the molds without danger thereto.

95

I am aware that various of the details of construction, as set forth, may be modified without departing from the spirit of the invention in its broader aspects, and I therefore do not desire to be limited as to these, or in any other respects, except as set forth in the appended claims.

95

Having described my invention, what I claim as new and desire to secure by Letters Patent is:

100

1. A mold extractor for molding apparatus, having a plunger-like upper end adapted to have a mold with its holding frame fitted thereon, pivoted arms for engaging said frame to draw it down over said extractor end, means normally pressing said arms in a direction for engagement with parts of said frame, and means for lowering said arms.

105

2. A mold extractor for molding apparatus, having a plunger-like upper end adapted to have a mold with its holding frame fitted thereon, pivoted arms for engaging portions of said frame to pull it down over said extractor end, spring means adapted to press said arms in a direction to engage said frame, and an oscillating shaft having lever arms engaged with said pivoted arms to lower them.

110

3. A mold extractor for molding apparatus, comprising a strap pocket adapted to be fixed to a support, a plunger block removably clamped in said pocket, the top of said block being adapted to have a mold with its holding frame fitted thereon, pivoted arms mounted adjacent said pocket in position to engage said frame when fitted on said plunger, and means for lowering said arms.

115

4. A mold extractor for molding appa-

120

125

130

ratus, comprising a plunger block having its top adapted to have fitted thereon a mold with its holding frame, the top of said block being recessed to afford guiding and stop means for said frame, and means for forcing the frame downward to remove the mold therefrom.

5. A mold extractor for molding apparatus, comprising a plunger block having its upper end formed and recessed to have a mold with its holding frame guided and held within limits of movement thereon, there being cut-out portions in said block top beneath the pattern impression in the mold.
- 10 15 6. A mold extractor for molding appa-

ratus, comprising a plunger block of insulated fiber formed and adapted to have a mold with its holding frame fitted thereover, the sides of said block serving as guides for the frame as it is forced downward, and the 20 block edges adjacent the frame having protecting wear plates fitted thereto.

In testimony whereof, I have signed my name to this specification, in the presence of two subscribing witnesses.

WILLIAM H. FORD.
